Attorney, Agent, or Firm—C. A. Phillips

[57] CLAIM

The ornamental design for a plow assembly, substantially as shown and described.

DESCRIPTION

FIG. 1 is a perspective view of the plow assembly of my design as seen from an upper rear right side point of perspective. A view seen from a like but left side point of perspective would be identical, except that it would be a mirror image of the view shown in FIG. 1.

FIG. 2 is a perspective view as seen from the lower rear right side of the plow assembly. A view as seen from the lower rear left side of the plow would be a mirror image of the view shown in FIG. 2.

FIG. 3 is an enlarged perspective view as seen from one side of the front of the plow assembly, with the portion behind the extreme front portion of the plow assembly being broken away. A view of that portion of the plow shown in FIG. 3 as seen from the opposite front side to that of the point of view of FIG. 3 would be a mirror image of the view shown in FIG. 3.
